UNITED STATES PATENT OFFICE.

JOSEPH J. LASHER, OF RICHMOND HILL, AND WALTER B. WASSUNG, OF NEW YORK, N. Y.

COIN-CONTROLLED MECHANISM.

1,149,270.

Specification of Letters Patent. Patented Aug. 10, 1915.

Application filed August 18, 1914. Serial No. 857,299.

To all whom it may concern:

Be it known that we, JOSEPH J. LASHER and WALTER B. WASSUNG, both citizens of the United States, and residents, respectively, of Richmond Hill, county of Queens, and State of New York, and borough of Brooklyn, city of New York, in the county of Kings and State of New York, have invented certain new and useful Improvements in 10 Coin-Controlled Mechanism, of which the following is a specification.

Our invention relates to a sanitary toilet device and refers particularly to a new and valuable sanitary toilet seat and operative 15 means connected therewith.

One object of our invention is a toilet seat which when not in use will be subjected to a disinfecting and germicidal reaction.

Another object of our invention is a toilet 20 seat which when released will be automatically subjected to a disinfecting and germicidal chemical.

Another object of our invention is a toilet seat which when released will be automatically subjected to a disinfecting and germicidal chemical and will be held in that position until released therefrom either with or without a coin operating mechanism.

The insanitary, unhygienic and objectionable 30 results incident to the general use of public toilets are fully recognized and numerous attempts have been made to overcome these objectionable features, but they have all presented difficulties that have prevented their general adoption.

Our invention is a device, simple in construction, easy of manipulation, inexpensive to manufacture, and absolutely effective in accomplishing the desired sanitary effect.

It possesses the further advantage that it 40 can be used in conjunction with the public seat, allowing of the use of either the ordinary seat or our sanitary seat, as the user may desire, thus not interfering with the rights of the public, should the owner of our device desire to make a charge for its use.

Our invention comprises broadly a movable toilet seat, which when not in use or released from retention, automatically 50 posits itself into a position where its upper surface is subjected to the disinfecting and germicidal action of the proper chemicals,

and remains in such contact until it is to be used. If it is desired to lock or hold the seat in this position until mechanically released either with or without the assistance of a coin, proper mechanism may be employed to accomplish this result, although we do not limit ourselves to such a mechanically released device.

The disinfecting receptacle of our device has a recess upon its face into which the seat fits, the surfaces of the recess in contact with the seat having perforations into the disinfectant holding chamber, thus causing the fumes of the disinfectant to come into contact with the upper surface and sides of the seat, or only the upper surface and inner side of the seat may be so treated if desired. The advantages of such a recess 70 are evident as it prevents any undue loss of disinfectant during the period in which the seat is not used, and disinfects all the surfaces of the seat which are liable to come into contact with the body during its 75 use.

As a disinfecting medium any disinfectant or germicidal compound may be used, the fumes of which are effective for the purpose described, but we prefer to use formaldehyde for this purpose.

The accompanying drawings illustrate one form of our invention, in which the employment of a coin is necessary in order to release the toilet seat from the disinfecting 85 recess.

Figure 1 illustrates a front plan view showing the toilet seat in its vertical position. Fig. 2 illustrates a cross-section view through the line 2-2 of Fig. 1. Fig. 3 90 illustrates a front plan view showing the toilet seat in its horizontal position and partly broken away to show the disinfectant absorbent. Fig. 4 illustrates a cross-section view through the line 4-4 of Fig. 3, the plunger-rod being pushed down. Fig. 5 95 illustrates a back elevational view with the back of the inclosing box removed to show the locking and releasing mechanism, and partly broken away to show the disinfectant absorbent. Fig. 6 illustrates a cross-section view through the line 6-6 of Fig. 5. Fig. 7 100 illustrates a plan cross-section view through the line 7-7 of Fig. 3. Fig. 8 illustrates

a cross-section view through the line 8-8 of Fig. 5. Fig. 9 illustrates a cross-section view through the line 9-9 of Fig. 5.

The following is a description of the form of our device as illustrated in the accompanying drawings.

The box 10 is composed of the front 11, the top 12, the bottom 13, the sides 14, 14, and the back 15. The front 11 has an elliptical opening 16, for purposes described later and the back 15 is removable in order to gain access to the interior of the box 10. A disinfecting receptacle is comprised of the back 17, the side 18 and the front 19 which is extended inwardly toward the center then perpendicularly outwardly at 20 and finally inwardly at 21, thus forming a receptacle which will fit flush against the inward side of the front 11 of the box 10, and extend outwardly through the opening 16 of the box 10 forming an elliptical channel 22 between the central member 21 of the disinfecting receptacle and the inner edge of the opening 16 of the box front 11. That portion of the disinfecting receptacle behind the front 11 of the box 10 contains a wick or absorbent material 23 capable of holding a disinfecting liquid, which liquid is introduced through the closable opening 24 in the back 17. The surface 20 and the front 21 are perforated in order to allow the disinfecting fumes to escape from the disinfecting receptacle. The channel 22 is of such a size and shape as to allow of the close receipt of a toilet seat 25, the upper surface and interior edge of the opening of which, when in this position, are subjected to the disinfecting fumes passing through the perforations in 20 and 21.

The plunger rod 26 passes through the top 12 of the box 10 and extends downwardly being loosely pivoted at 27 to the arm 28 which is fixedly attached to or integral with the bar 29, revolvable in the brackets 30, 30 attached to the bottom 13 of the box 10.

Fixedly attached to the bar 29 are the arms 31, 31, pivotally attached at 32.32 to the arms 33,33 which are in turn pivotally attached at 34.34 to the arms 35.35. The arms 35.35 are fixedly attached to the bar 36, revolvable in the brackets 37.37 attached to the front 11 of the box 10. The bar 36 carries the fixed arms 38.38 fixedly attached to the seat 25. The plunger operating device described above is so arranged that the downward movement of the plunger 26 will revolve the bar 29 which in turn will revolve the bar 36 by means of the link system 31, 33, 35, the revolution of the bar 36 carrying the toilet seat from its vertical position in the disinfecting channel 22 outwardly and downwardly until it rests horizontally over the toilet bowl 39. A spiral spring 40 surrounds a portion of the rod 29,

having its ends affixed to the bracket 30 and the link member 31, so that when the pressure upon the plunger 26 is removed, and the seat 25 is released from retention, the action of the spring will cause the seat 25 to assume its vertical position in the disinfecting channel 22.

A coin mechanism disposed to lock the seat in its vertical position and to release the seat when by the insertion of a coin in conjunction with the plunger movement comprises a coin chute of an irregular Y shape, in which one arm 45 extends directly upwardly from the arm 44 and the other arm branches off diagonally upward 43 and then vertically upward 42 being integral with the coin opening 41 in the top 12 of the box 10. The arms of the coin chute are of a diameter and width to allow of the ready passage of a proper coin. The plunger 26 carries a flat arm 46 extending therefrom and through a vertical opening 47 in the coin chute arm 45, the extremity of the arm 46 carrying a flat arm 48 perpendicular thereto, slideable within the chute arm 45 and extending downwardly toward the branching point of the chute arms 43, 44 and 45.

Pivoted to the supporting member 49 at 50 is the locking member, shown in detail in Fig. 5 and Fig. 8, which comprises the bar 51 held in the groove 52 of the plunger 26 by the spring 53 attached to the end of the bar 51 and the supporting member 49. The other end of the bar 51 is extended into an inverted U shaped element 57 having an inset 54 in its upper member, so arranged that when the locking member is in its normal position, the bar 51 will set in the groove 52 preventing the pushing down of the plunger, and a coin 55 inserted in the slot 41 will fall down the chutes 42, 43 and rest against the wall of the coin chute and the inset 54 of the locking member as shown at 56 of Fig. 6. The mechanism will then be in the position indicated by the full lines of Fig. 8. If now the plunger rod 26 be pressed downwardly, the member 46, 48 will move downwardly through the coin chute arm 45, and the lower end of the arm 48 will engage with the edge of the coin which will be pressed downwardly, the diameter of the coin pressing against the locking member 57 forcing it outwardly, releasing the bar 51 from the groove 52 of the plunger rod 26, thus allowing a further downward movement of the plunger rod 26, and the forcing of the coin completely past the locking member 57, causing it to fall down the coin chute 44 into the coin receiver 58. The position of the locking member, during the passage of the coin and the releasing of plunger rod is shown by the dotted lines in Fig. 9. The distance between the wall of the coin chute

and the inset 54 is such as to hold and maintain a coin of the proper diameter, but which will allow a coin of smaller diameter as 59 to pass through into the coin receiver 58 without allowing of the unlocking of the plunger rod, thus preventing the working 5 of the mechanism by means of a coin of less diameter than that desired. The width of the groove 52 must be sufficiently large 10 to allow of the downward movement of the plunger rod 26 a distance great enough to cause the coin to operate upon the locking device and free the bar 51 from the groove 52. When the coin has passed through the 15 chute and the plunger rod 26 is returned to its original position, the bar 51 slips into the groove 52 locking the rod from further movement except upon the introduction of another coin.

20 A toothed pawl 60 is pivotally attached at 61 to the front 11 of the box 10 and so positioned as to pass along the plunger rod 26 when the latter is moved and catch in the inset 62 of the plunger rod 26, when the 25 rod is at its lowest position. The pawl 60 is maintained in the inset 62 by the spring 63 connected with the pawl 60 and the member 64 attached to the supporting member 49. The purpose of the pawl member 30 60 being explained later.

Upon the plunger rod 26 is the spring operated pawl 64 which during the downward movement of the rod 26, acts upon the ratchet wheel 65, causing it to rotate and 35 record the number of movements of the plunger rod upon a counting device 66.

The coin receptacle 58 may have a door 67 and lock in the rear wall 15 of the box 10.

The entire mechanism is shown hinged to 40 a wall as at 68, 68 in order that it may be swung away from the wall and the interior examined from the rear of the box 10, it being locked to the wall by means of the hasp lock 74.

45 The seat of our device may be used alone upon a toilet bowl, or in conjunction with the ordinary seat, and in the drawings it is shown as used in conjunction with the regular seat 69, the seat 25 of our mechanism when in use being situated over the regular seat, and protected therefrom by the rubber cushions 70, 70.

The pipe 71 connects the bottom of the disinfecting receptacle with the toilet bowl, 55 the connection 72, being one that is easily severed as by means of a coupling in order that it may be disconnected when it is desired of swinging the device upon the hinge 68, 68.

60 When our device is in its normal condition, the seat 25 is in a vertical position resting in the channel or recess 22 and being subjected to the germicidal action of the fumes from the disinfecting receptacle. The 65 seat is held and locked in this position by

the bar 51 resting within the groove 52 of the plunger rod 26, thus preventing the downward movement of the latter. A coin of suitable diameter is introduced through the coin slot 41, and falls through the arm 70 42, 43 of the coin chute and rests between the front wall of the box 10 and the wall of the coin chute as at 56. The plunger rod 26 is then moved downwardly, the plunger rod members 46, 48 being thus passed downwardly within the coin chute member 42, 75 the arm 48 pressing upon the upper edge of the coin, and forcing the arm 51 outwardly, allowing the coin to fall downwardly into the coin box 58 at the same time releasing 80 the arm 51 from the plunger rod groove 52, and allowing a further downward movement of the plunger rod 26. As the plunger rod descends, it revolves the bar 29 by means of the link 28, which in turn causes a revolution of the bar 36 through the medium of the link system 31, 33, 35. As the bar 36 revolves it brings the seat 25 downwardly and outwardly toward a horizontal position. When the plunger rod 26 has descended 90 until it has reached its lowest position, the pawl 60 rests within the inset 62 of the plunger rod 26, and the seat 25 is held in the position shown by the dotted lines 73 of Fig. 4, in which position it is held when 95 the plunger rod is released. At the same time the pawl 64, has registered upon the counting device 66 by the revolution of the ratchet wheel 65. The seat 25, as shown at 73 of Fig. 4 is then pulled downwardly 100 until it is in a horizontal position resting upon the regular seat 69, this downward movement causing the pawl 60 to leave the inset 62 thus releasing the plunger rod 26. When the seat 25 is released from retention 105 in its horizontal position, the spring 40 causes it to again resume its vertical position in the disinfecting channel, in which position it is locked until released by the introduction of another coin. As the seat 110 25 is thus returned to the disinfecting channel, it forces a certain amount of air through the perforations in the disinfecting receptacle, thus forcing air carrying the disinfecting fumes downwardly through the 115 pipe 71 and into the bowl 39.

We do not limit ourselves to the size, shape, number or arrangement of parts as shown and illustrated all of which may be varied without going beyond the scope of 120 our invention as described and claimed.

What is claimed, is:

In a device of the character specified, in combination, a coin chute, a plunger rod exterior to the coin chute carrying an extended arm movable within the coin chute, a recess within said rod, locking means engaging in said recess for preventing the downward movement of the rod, and preventing a coin from passing entirely down 130

the coin chute, so situated that an inserted coin will pass partially down the chute and be retained between the locking member and the extended arm of the rod, the extended arm of the rod being so situated that the downward movement of the rod will press the extended arm upon the coin, releasing the locking member from the plunger rod, allowing its downward movement and allowing the passage of the coin down the chute, and means for returning the rod

Copies of this patent may be obtained for five cents each, by addressing the "Commissioner of Patents, Washington, D. C."

to its original position, allowing the locking member to engage within the recess to prevent the downward movement of the rod.

Signed at New York city, in the county 15 of New York and State of New York, this 12th day of August, 1914.

JOSEPH J. LASHER.

WALTER B. WASSUNG.
